UNITED STATES PATENT OFFICE.

WILLIAM C. STEWART, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

HEEL-SEAT FITTING MACHINE.

Application filed September 18, 1924, Serial No. 738,449, and in Great Britain May 16, 1924.

This invention relates to machines for use in the manufacture of shoes and is illustrated herein as embodied in a heel seat fitting machine.

5 In the manufacture of shoes to which certain types of heels are to be attached, the heel seat portions of the soles of the shoes are prepared for the attachment of heels by a trimming operation called heel seat fitting. 10 Heels of the types referred to, of which wood heels at the present time are by far the most important examples, are formed with concave attaching surfaces, and it is the purpose of the heel seat fitting operation to 15 shape the heel seat portion of the sole so that the periphery of the concave attaching surface of the heel will contact closely with the adjacent shoe upper. Thus the margin of the heel seat portion of the sole is completely covered by the attached heel and is 20 not visible in the completed shoe. The convex shape given to the heel seat of a shoe by the heel seat fitting operation is supplemental to the shape of the attaching surface 25 of a wood heel and accordingly provides a good bearing for the heel upon the sole.

For many years this operation was invariably performed by hand. More recently machines for this purpose have been introduced and successively used. It is an object of the present invention to provide a simplified and improved machine by the use 30 of which heel seat fitting operations may be still further facilitated.

35 The stock trimmed from the heel seat portion of the sole of a shoe during the heel seat fitting operation is roughly of a horse-shoe-shaped form, a breast cut or cuts being made transversely of the sole to receive the breast of the heel. The position of the breast cut longitudinally of the shoe and both the width and the length of the horse-shoe-shaped trimming cut must, however, be varied in accordance with the size and style 40 of the heel to be attached. Accordingly, features of the present invention comprise improved means for controlling the location of the breast cut and for controlling the form and extent of the trimming cut.

45 Other features of the invention comprise an improved mounting for a knife which cuts a transverse heel breast receiving flap, so as to facilitate the accurate adjustment

of the knife, and devices for controlling the work including means for deflecting the heel 55 breast receiving flap from the knife in order to reduce friction and prevent binding.

A further feature of the invention comprises an improved organization including work-supporting means by which the shoe 60 operated upon may be properly presented to the operating instrumentalities of the machine. The illustrated work-supporting means causes the shoe to be supported with a comparatively light upward pressure during the trimming operation and to be pressed upwardly with a greater force during the making of the heel breast receiving cut, as has been found most desirable in a machine of the type herein disclosed. 65

70 Further features of the invention relate to an improved organization for operating and controlling the tool which makes the trimming cut. In order to simplify the machine and to improve its operation, as illustrated 75 herein, a rotating cutter is mounted directly on the rotor shaft of a motor which travels with the cutter about the periphery of the heel seat portion of the sole of the shoe operated upon, and to insure that the motor shall 80 not be left running needlessly when the machine is not operating, means is provided for cutting off the source of power from the motor when the trimming tool is moved out of operative relation to the work and for 85 connecting the motor with the source of power when the cutter is moved toward its operative position.

90 While the invention is herein disclosed as embodied in a heel seat fitting machine in which a shoe is held stationary while it is operated upon by a rotary cutter moving about the periphery of the heel seat portion of the sole and by a transversely moving knife which cuts a flap at the forward extremity of the heel seat, it should be understood that this machine is primarily illustrative and that in various of its aspects the invention is not limited to a machine of this 95 type.

100 With the above objects and features in view, the invention will now be described in connection with the accompanying drawings and pointed out in the claims.

Fig. 1 is a perspective view of the machine 105 as a whole.

Fig. 2 is a front elevation of the upper part of the machine with the breast knife at the end of its stroke;

Fig. 3 is a plan view of the work-supporting crease plates;

Fig. 4 is a plan view of a portion of the mechanism for controlling the path of the rotary cutter;

Fig. 5 is a detail view of part of the electric control mechanism;

Fig. 6 is a perspective view of the operating end of the breast knife bar;

Fig. 7 is a transverse section through the breast knife;

Fig. 8 is a plan view of the heel seat portion of a shoe showing the work done by the machine;

Fig. 9 is a side view of the heel portion of the same shoe;

Fig. 10 is a view partly in section of the control dials for adjusting the machine to operate upon heels of different sizes and styles;

Fig. 11 is a front elevation of the spindle and the elevating mechanism therefor; and

Fig. 12 is a vertical section showing the spindle tipped forward.

In carrying out the heel seat fitting operation, the illustrated machine is arranged to remove surplus material from the periphery of the heel seat portion of the sole of a shoe by means of a milling cutter moved manually with respect to the suitably supported shoe under the guidance of an adjustable templet. The breast cut, which is shown as inclined forwardly and downwardly to provide the short thick flap to receive the forwardly extending breast of a Louis heel, is then made by means of a transversely moving knife which enters one lateral edge of the sole and passes across the sole at the desired inclination to its surface. In view of the variation in the styles and sizes of heels to be applied, means are provided for adjusting the controlling templet for the movable cutter so that the work may be accurately yet speedily accomplished. In the preferred form of the invention the adjustment is effected by turning one or both of a pair of dials, one of which is graduated to correspond with various styles of heels while the other is graduated to correspond to various sizes of heels. In the use of the machine it is only necessary to adjust the style dial infrequently when changing from one lot to another lot of shoes, while it will be necessary to adjust the size dial as often as the size of heel to be attached is changed. In general the machine comprises a framework on which there is pivotally mounted a last-supporting spindle and co-operating work-positioning and supporting crease plates above said spindle so that after the lasted shoe has been mounted on the spindle, it may be swung away from the operator to

bring the shoe into engagement with properly shaped, movably mounted crease plates arranged to enter the rand crease of the shoe for gripping engagement therewith. A sliding table mounted above the work-supporting mechanism is provided with a vertical motor-driven spindle on the lower end of which is mounted a suitably shaped tapered milling cutter. An adjustable templet for controlling the path of movement of said spindle relatively to the work is provided, and after the carriage has been moved forward to present the tool in operative relation to the heel seat portion of the shoe, the cutter spindle is moved in a horseshoe-shaped path to carry the cutter around the rear of the heel seat portion of the sole. The tool-carrying table is then moved out of operative position and a transversely moving knife bar is actuated to force a knife laterally through the sole from one side to the other to cut the tapered tongue which has been described above.

The frame of the illustrated machine comprises leg castings 20 and 22 on the top of which there is supported a bed casting 24 recessed at the front at 26 to provide room for the work. The legs are held in proper spaced relation at the bottom by means of crossbars 28 and 30 and by means of a cross-frame 32. Work to be applied to the machine is supported primarily upon a spindle or post 40 in which is mounted for lengthwise movement a hollow shaft 41 carrying at its upper end a tapered last pin 42 which is slidably adjustable laterally, as is indicated in Fig. 12, in a manner already well understood in the art. A spring 43 housed within shaft 41 tends to lift shaft 41 and last pin 42, such movement being limited by a crew 45 threaded in spindle 40 and entering a slot 47 formed in rod 41. The spindle 40 is pivotally supported between ears 44 upon the cross-frame by means of a bearing block 46 (Fig. 12) provided with trunnions pivoted in said ears. The spindle 40 is provided with a downwardly extending pin 48 which is slidable vertically with respect to said bearing block 46 and may be engaged by a transverse lever 50 fulcrumed at 52 upon the cross-frame 32 when the spindle is in a substantially vertical position so as to raise it to press the work firmly into engagement with work-supporting crease plates to be later described. A spring 54 extending between the cross-frame 32 and a pin upon the bearing block 46 tends to tip the spindle 40 forward and to bring it into accessible position for the placing of a piece of work thereon by the operator. Still another spring 56, extending between the spindle 40 and the bearing block 46, tends to lower said spindle when the spindle has been released by tilting forward or by the depression of the lever 50.

A bed plate 60, recessed at the front to admit the heel end of a shoe, is suitably secured to the bed 24 of the machine and supports movably a pair of work-engaging and supporting crease plates 62 (Figs. 1, 2, and 3). These plates have the work-engaging edges thereof tapered, as indicated in Fig. 2, and by a pivotal adjustment around a center 64 (Fig. 3), which coincides substantially with the back seam of a shoe, the plates are adapted to be brought into close engagement with the crease between the sole and the counter portion of the upper of a shoe. Each plate is removably secured upon a segmental plate 66, which is received within a recess in the bed plate 60 and is provided upon its peripheral portion with a groove, best shown in Fig. 1, which receives a depending rib upon a retaining plate 68. Actuation of these crease plates is effected means of links 70 pivotally attached to the supporting plates 66 and extending rearwardly therefrom through grooves in the bed plate 60, indicated by dotted lines in Fig. 3. The links 70 are pivoted at a common point by a pin 72 to the end of a link 74, which is pivotally attached at 76 to a fixed portion of the bed 24. A grooved track 78 is also provided upon the bed 24 for a transversely movable block 80 slotted at 82 to receive the depending end of the pivot pin 72. Actuation of this block transversely of the machine results in swinging the crease plates 62 gradually but positively around the center 64 to bring them firmly into engagement with the shoe. Movement of the slotted block 80 may be secured by means of a bell crank 84 connected by a link 86 to the upwardly extending arm 88 of an L-shaped lever 90 pivoted at 92 to the bed 24 of the machine and provided at its forward end with a handle 94 (Fig. 1) for engagement by the operator. A pawl 96 designed to engage with a ratchet 98 enables the operator to lock the lever temporarily in position after the crease plates have been brought into engagement with the shoe.

In order that the crease plates may not be concealed by other parts of the operating mechanism while the work is being introduced or removed, the cutting mechanism is supported upon a sliding table adapted to be moved back so that the operator may see the work as it is positioned in the machine. The cutter-carrying table is then moved forward into operative position and the cutter guided around the periphery of the heel seat portion of the sole supported just above the crease plates 62. To this end the bed 24 is provided with lateral upright portions 100 and 102 provided with horizontal tracks 104 for the support and guidance of a tool-carrying table 106 adapted to be moved forward and back in the machine by means of a hand lever 108 connected with said table

by an arm 110 and a link 112. A suitable pawl and ratchet is provided upon this lever to hold it in its forward position as determined by a stop 114 carried upon the lateral member 102. The table 106 comprises a lower plate 116 apertured at 118 (Fig. 4) to allow movement of the cutter shaft with respect thereto and an upper plate 120 spaced from the lower plate 116 and provided with a horseshoe-shaped slot 122 (Fig. 4).

The cutter shaft is supported in perpendicular relation to the plane of this table by means of a bearing sleeve 124 passing through the openings 118 and 122 and provided, between plates 116 and 120, with a disk-shaped extension 126 which fits snugly between said plates and provides a firm but readily movable bearing support for the cutter shaft, thus insuring that the cutter shaft is always maintained in perpendicular relation to the table and the work as it is moved about. In this sleeve 124 is a cutter shaft 130 to the lower end of which there is secured a trimming cutter illustrated as a milling cutter 132 which is preferably surrounded by a guard (not shown). The shaft 130 is directly connected to and forms an extension of the shaft of an electric motor 136 (Fig. 1) which is supported by brackets 138 from a plate 140 pivoted at 142 to an intermediate point of a lever 144 which is pivoted at its rear end to the upper plate 120 of the table and is provided at its forward end with a handle 146 by means of which it may be swung to move the cutter shaft transversely of the machine. The plate 140 slides on bearing strips 141 and is extended at its outer end and provided with a handle 148 by means of which the plate may be swung around its pivot 142 to move the cutter shaft forward and backward in the machine. Current may be applied to the motor in any suitable way, and the illustrated arrangement comprises a flexible cord 150 leading to a switch box 152. The path of the current to the switch box passes first, however, through a switch 154, best shown in Fig. 5, which is of a well-known type of construction provided with a spring-pressed plunger 156 arranged to break the circuit when the plunger is pressed in and to make the circuit when the plunger protrudes under the action of a spring. This plunger 156 is in the path of movement of the table 106 and is so arranged that movement of the cutter-carrying table to the rear of the machine automatically breaks the circuit to the driving motor, while movement of the cutter-carrying table to the front of the machine automatically closes the circuit and starts the motor ready for the operation of the machine.

In order that it may not be necessary for the operator manually to control accurately the movements of the cutter shaft as he

4

moves the cutter to trim away the peripheral portion of the heel seat of the shoe, a templet is provided designed to coact with the sleeve 124 surrounding the cutter shaft so that it is merely necessary for him to cause the cutter shaft to be moved from one extremity to the other of a horseshoe-shaped slot in said templet in order accurately to perform the trimming operation. This templet comprises plates 160 and 162 pivoted at 164 to the top plate 120 of the sliding table and provided near their forward ends with a horseshoe-shaped guideway or slot 166. As shown in Fig. 2 and indicated in Fig. 4, the plates 160 and 162 are provided with an overlapping joint in order to preserve the continuity of the slot 166 as said plates are relatively adjusted and the plates are urged toward one another by means of a spring 168 secured to pins projecting from their forward ends. It will be noted that the slot 166 is provided with an enlargement or vestibule 169 at its right forward end, and the cutter shaft is moved into this vestibule at the beginning and end of the cutting operation in order that the cutter may not come into contact with the work as the table is moved into and out of its forward position until the operator is ready to start the trimming operation. The plates of the templet are so located upon the moving table 106 that when the moving table is moved to its forward position, as determined by the stop 114, the slot 166 occupies a predetermined position vertically above the heel seat portion of the sole of a shoe which is held by the crease plates 62.

After the trimming of the peripheral portion of the heel seat has been accomplished and the cutter-carrying table 106 has been moved to the rear, a transverse cut in the sole adjacent to the breast of the heel is made by means of a knife entering the sole at one edge and movable across the sole from one edge to the other substantially at right angles to the edges of the sole. This knife is positioned at a slight angle to the plane of the surface of the heel seat and is passed across the sole, until it emerges at the other edge, to make a forwardly, downwardly extending cut which forms a thick tapered flap adapted to serve as an abutment for the breast of the heel. This construction will be better understood by reference to Figs. 8 and 9 in which there is shown a woman's shoe having an upper 350 mounted upon a last 352 and provided with a sole 354. Prior to its attachment to the shoe, the rear part of the sole has been split to provide a breast flap 356 of the usual form. In the operation of the machine, the periphery of the heel seat portion 358 is trimmed off at 360 in order that the upper edge of the heel may contact closely with the upper and that the recess in the heel may fit closely over the heel seat portion. The transverse cut made in the sole to form an inner tongue 362 is effected by means of a knife entering one edge of the sole and passing laterally thereto with its cutting edge extending through the heel seat of the sole from 364 (Fig. 8) to a line passing through the sole intermediate of its thickness at 366. After the heel seat fitting operation, the heel is applied to the heel seat over the fitted portion with its breast against the abutment 75 formed by the tapered flap or inner tongue 362 which is secured to the breast of the heel by glue or otherwise, after which the covering flap 356 is also secured to the breast of the heel to provide a finishing cover therefor. It will be understood that the heel may be secured to the shoe in any one of a variety of well-known ways.

In the illustrated machine, the transverse cut is made by a knife 170 having a beveled front edge 171 which does the actual cutting. Knife 170 is also beveled at 173 to produce a thin edge at one side, thereby permitting movement of the knife across the sole without tearing the leather of the sole. This knife is adjustably attached to and supported upon a knife bar 172 slidable transversely of the machine and guided in a correspondingly shaped bearing provided in a carriage 174. This carriage is in general of H-shaped cross-section, as shown in Figs. 1 and 2, and the cross-bar of the H is located in a slot formed in the lateral member 102 of the bed of the machine and is capable of adjustment forward and backward to bring the knife cut at the desired point in the heel seat in accordance with the size of the heel to be applied. The carriage 174 has a lateral extension 176 serving to make the bearing for the knife bar 172 more rigid. This extension has on its lower side a threaded sleeve 178 (Fig. 10) coacting with suitable adjusting means to be later described, by means of which the carriage 174 may be moved forward and backward as required to adjust the machine for operation upon different styles of heels. The knife bar may be actuated by means of a bell crank lever 180 (Figs. 1 and 2) pivoted upon a bracket on the frame member 22. As shown in Fig. 1, the upper end of the bell crank lever 180 is slotted for engagement with a pin 182 passing across the end of an enlarged slot in the end of the knife bar 172, thus allowing for adjustment of said knife bar with respect to the bell crank lever and lengthwise of a shoe on the work support without interfering with the proper coaction of the knife bar and the bell crank lever. At its other end the bell crank lever is connected to a rod 184 pivoted at its lower end to a rigid extension 186 (Figs. 1 and 11) of a treadle 188 pivoted at its rear end on the spacing rod 30 and normally maintained in upward position by a spring 190. Mounted

5 10 15 20 25 30 35 40 45 50 55 60 65 70 75 80 85 90 95 100 105 110 115 120 125 130

upon the rod 184 and resiliently held by a spring 192 against a collar 194 is an actuator 196 provided with a lateral extension 198 (Fig. 11) slidably engaging a vertical rod 200 guided in bearings 202 upon the cross-frame 32 and provided with a collar 204 for coaction with the extension 198. The lower end of the vertical rod 200 is reduced at 206 and passes through a slotted end 208 of the horizontal lever 50. By means of this arrangement, the depression of the treadle 188 not only moves the knife bar and the attached knife positively across the shoe but also lifts the spindle 40 through the effect 15 of the actuator 196 upon the horizontal lever 50, thus yieldingly but forcibly holding the work in position in the crease plates and insuring accuracy in the cutting action of the knife as it forms the breast cut in the 20 heel seat. A stop bar 210 (Fig. 1) is attached to the forward end of the sliding carriage 174 in such a position that it limits the forward movement of the cutter shaft in its templet slot by contacting with the 25 sleeve 124 in which said shaft is carried, so as to limit the forward extent of the trimming cut in accordance with the position of the breast cut.

Inasmuch as the effect of the actuator 196 upon the transverse lever 50 in holding up the spindle 40 is only effective during the time that the knife is making the breast cut, other means are provided for holding up said spindle when making the peripheral cut. These means are best illustrated in Fig. 11, from which it will be seen that the table moving lever 108 is provided with an extension 212 connected to a vertical rod 214 surrounded by a sleeve 216 which is resiliently held against a stop collar 218 by a spring 220. The right-hand end of the lever 50 is slotted and surrounds said sleeve 216 resting against a shoulder 222 thereon so that when the hand lever 108 is actuated to pull the cutter-carrying table into forward position the lever 50 is lifted resiliently to hold up the spindle so as to maintain the work in proper position with respect to the crease plates 52. The spring 220 should be lighter than the spring 192 for the reason that it is not necessary to exert as much tension in holding up the spindle during the time that the peripheral cut is being made as it is necessary to exert when the transverse cut is being made and by reason of the differences in the lengths of the lever arms involved.

The detailed construction of the connection between the knife 170 and the knife bar 172 is shown particularly in Figs. 6 and 7. Knife 170 is rigidly attached to a carrier block 230 having a curved outer surface 232 coacting with a similarly shaped surface upon the knife bar 172 and clamped in position with respect thereto by means of a

screw stud 234 passing through a slot in said knife bar, as indicated by dotted lines in Fig. 7. To assist in the adjustment of the knife carrier 230 when screw stud 234 is released, set screws 236, passing through the knife bar and engaging the upper edge of the curved surface 232, are provided. A guard or plow 240 is attached by screws to the knife block 230, the lower edge of said plow 240 being in close relation to the lateral cutting edge of the knife 170, and the plow is provided with a tapered projection 242 at its forward end adapted to engage under and lift up the flap formed by the action of the knife to prevent interference there-between and the knife bar 172 as the cutting action progresses. Any tendency of the sole to buckle or lift away from the last during the cutting action of the knife 170 is prevented by a presser member comprising a tapered roll 244 carried in front of the front cutting edge 171 of the knife 170 by means of a hinged plate 246 carried upon the end of a horizontal plate 248 adjustably attached by a hinge 250 to the knife bar 172 and raised or lowered with respect to said bar by means of an adjusting screw 252. The roll 244 is larger at the end overlying the lateral beveled edge 173 of the knife 170 which cuts more deeply into the work. Greater pressure is thus provided where it is needed. A spring 254 passing between the vertical hinged plate 246 and the knife bar 172 normally holds the carrier for said tapered roll 244 in a vertical position determined by a stop 247 (Fig. 2) extending out from the end of the knife bar 172 to engage with the back side of said plate 246 when the knife bar is moving forward. During the rearward movement of the knife bar, however, the spring 254 allows the roll carrier 246 to be lifted, thus avoiding possible damage to the shoe.

As has been stated in an early part of this specification, variations in styles and sizes of wood heels, which means variations in both their widths and lengths, render necessary some means for varying the position of the breast cut, for varying the extent of the peripheral or trimming cut, and for determining the adjustment of the templet controlling the width or spread of the horse-shoe-shaped path through which the trimming cutter moves. To these ends, mechanisms are provided whereby the elements of the machine may be adjusted to compensate for variations in the styles of heels and other adjustments made to compensate for variations in the sizes of heels of a given style. Inasmuch as the adjustments for the size of the heel must be made most frequently, a conveniently located, manually operated size dial 260 (Figs. 1, 2 and 10) is provided near the front left-hand side of the machine, and this dial, which is gradu-

ated in accordance with the scale of sizes used for wood heels, may be set with reference to a pointer 262 (Fig. 10) mounted upon a bracket 264 extending out from the frame of the machine with very slight effort upon the part of the operator so that templets 160, 162, which control the spread of the path of the trimming cutter may be adjusted to control the width to which the heel seat of a sole is trimmed. Since the graduations of the size dial correspond to the widths of the different sizes of heels of a given style, the setting of the size dial permits the trimming of the heel seat to a width corresponding to that of the size of heel for which the size dial 260 is set. The setting of the size dial 260 also controls the extent of the trimming cut lengthwise of the shoe and the position of the breast cut through connections hereinafter described.

Since the relation of the length to the width of heels of the same nominal size but of different styles varies, mechanism is also provided for changing the extent lengthwise of the shoe of the trimming cut and the position of the breast cut relatively to the width to which the heel seat is trimmed. This is done by mechanism arranged to adjust the carriage 174 forward or backward. The carriage 174, it will be remembered, carries the knife bar 172 and the limiting stop bar 210 so that the position of the carriage 174 controls both the forward extent of the trimming cut and the position of the breast cut. The mechanism for effecting this movement of carriage 174 is controlled by a graduated style dial 266 located at the rear of the size dial 260. A fixed pointer 268 is positioned adjacent to the style dial 266 to provide a point of reference with respect to which that dial may be set. The relation of the graduations on the style dial to the various heels which are to be attached to the shoes to be operated upon is determined at the start and a chart setting forth the proper setting of the style dial 266 for each of the various styles of heels in use in the factory may be prepared and posted in a convenient place. The style dial 266 is held in position frictionally by means of a screw 270 (Fig. 1) engaging a tubular extension of the dial and is provided with a stop pin 272 adapted to engage a coacting pin 274 in the bracket 264 to limit the movement of the dial to something less than one complete revolution. A similar stop pin 276 in the size dial coacts with the other end of the pin 274 similarly to limit the range of movement of the size dial 260.

The size dial is attached to a threaded shaft 280 (Figs. 1 and 10) extending toward the rear of the machine and connected by mitred gears 282 with a stub shaft 284 supported in a bracket 286 on the frame member 102. On the upper end of the stub shaft

284 is a cam 288. A bar 292 (Figs. 2 and 4) is supported upon the parallel arms of bell crank levers 294 and 296 carried in brackets on the frame member 102 for parallel movement transversely of the machine. Supported upon the other arms of the bell crank levers 294 and 296 is a bar 300 having a roll 290 mounted on and depending from its lower surface and positioned in the track of cam 288. The upper surface of bar 300 is grooved at 302 to receive and control the movements of a roll 304 depending from one arm of a bell crank lever 306 (Figs. 1 and 4) pivotally attached at 308 to a bracket 310 secured to the upper face of the table 106. The movements of this bell crank lever 306 are made effective to open or close the templet plates 160, 162 by connecting the other arm of said lever to one end of a lever 312 (Fig. 4) fulcrumed at 314 on the table 106 and provided with pins 316 and 318 engaging slots 320, 322 in said templet plates, the direction of the slots 320 and 322 being such that pivotal movement of the lever 312 about its fulcrum opens said plates against the tension of the spring 168 or allows them to close, thus determining the width of the templet slot. It will be noted that the connection between the bell crank 306 and the lever 312 is provided by means of a stud 324 (Fig. 4) which may be adjustably positioned with respect to the bell crank 306 in an enlarged opening 326. It will also be noted that, by reason of the groove 302 in the bar 300, the adjustment of the templet plates is not disturbed by forward and backward movement of the cutter-carrying table 106 with respect to the cam-controlled, parallel bars 292 and 300.

The mechanism hereinbefore referred to for changing the relation of the position of templets 160, 162 to the position of carriage 174 and, accordingly, for controlling the relation of the width to which the heel seat is trimmed to the forward extent of the trimming cut and the position of the breast cut, so as to adapt the machine to operate on heels of different styles, will now be described. Mechanism for effecting this adjustment is best shown in Figs. 1 and 10, from which it will be seen that the horizontal shaft 280 is externally threaded with a screw thread of long pitch which is in threaded engagement with the interior of a tubular extension or sleeve 330 forming part of the style dial 266. The extension 330 is also externally threaded to screw in the interior of the sleeve 178 upon the lower face of the lateral extension 176 of the carriage 174.

Referring now to Fig. 10, when the size dial alone is rotated, the spread of templets 160, 162 is changed by reason of the connections operated by the rotation of shaft 280. The engagement of sleeve 330, carried by the

- style dial 266, with threaded shaft 280 is such that the style dial moves bodily lengthwise of shaft 280, carrying with it the lateral extension 176 of carriage 174 and carriage 174 itself. Thus the longitudinal extent of the heel seat, as well as the width, is varied by rotation of the size dial 260, the variation produced by rotating the size dial the distance between two consecutive graduations 10 corresponding to the difference between the consecutive sizes of heels. When the style dial 266 is rotated, it travels lengthwise of shaft 280 by reason of the screw connection between the two and carries sleeve 178, extension 176 and carriage 174 bodily with it. At the same time, on account of the threaded connection between sleeve 330 and sleeve 178, the latter, together with extension 176 and knife bar 172, is moved additionally an amount depending upon the pitch of the thread of sleeve 330. Thus when the style dial 266 is moved, the resulting movement of carriage 174 is determined by the combined effects of the external thread of sleeve 330 engaging with the thread of sleeve 178 and the internal thread of sleeve 330 engaging with the thread of shaft 280. As shown in Fig. 10, these threads are arranged in opposite senses, being right and left-handed respectively. On the other hand, when the size dial 260 is moved, the resulting movement of carriage 174 is determined merely by the pitch of the thread upon shaft 280.
- 30 A dust-collecting hood 340 may be provided at the rear of the machine for connection to a suction pipe so as to remove the chips cut off by the milling cutter.
- Having described the invention, what I claim as new and desire to secure by Letters Patent of the United States is:
1. A heel seat fitting machine provided with a shoe support and a cutter arranged to trim surplus material from the entire periphery of the heel seat of a shoe carried on said support, said support and cutter being mounted to permit relative movement of the shoe and the cutter during the trimming operation in a path corresponding to the contour of the heel seat of a shoe, means for controlling the relative movement of the shoe and the cutter, a graduated dial, and means connecting said dial to said controlling means to vary the contour of the path of relative movement of the shoe and the cutter in accordance with the setting of the dial.
  2. A heel seat fitting machine having a shoe support and a rotary cutter, said support and cutter being mounted for relative movement to permit the cutter to trim surplus material from the entire periphery of the heel seat portion of a shoe upon the support, adjustable means for controlling the relative movement of the support and the cutter, a graduated dial, and means connecting said dial to said controlling means to vary the contour of the path of relative movement of the shoe and the cutter in accordance with the setting of the dial.
  3. A heel seat fitting machine having a shoe support, a knife, means for causing relative movement of the knife and the shoe support transversely across the sole of a shoe upon the support, from one edge of its sole to the other, to cause the knife to make a heel breast receiving cut extending across the sole substantially from one edge to the other at the heel breast line, adjustable means for controlling the relative movement of the support and the knife, a graduated dial, and means connecting said dial to said controlling means constructed and arranged to vary the relative movement of the knife and the shoe support in accordance with the setting of the dial so as to make the breast cut upon the sole of the shoe to fit the particular size of heel indicated by the dial.
  4. A heel seat fitting machine provided with a movable cutter, means for guiding said cutter around the heel seat of a shoe to trim the periphery of the heel seat, a graduated dial, and means for connecting said dial to said guiding means constructed and arranged to determine the extent of the cut longitudinally of the shoe in accordance with the setting of the dial.
  5. A heel seat fitting machine provided with a movable cutter, means for guiding said cutter around the heel seat of a shoe to trim the periphery of the heel seat, a graduated dial, and means connecting said dial to said guiding means constructed and arranged to determine the spread of the path of the cutter as it moves around the heel seat in accordance with the setting of the dial.
  6. A heel seat fitting machine provided with a movable cutter, means for guiding said cutter around the periphery of the heel seat, a dial having graduations corresponding to the relation of the length to the width of the heel seats of different styles of heels, and means for connecting said dial to said guiding means constructed and arranged to cause adjustment of said dial to control the path of the cutter so that the periphery of the heel seat may be trimmed to correspond to the heel seats of different styles of heels.
  7. A heel seat fitting machine having a rotary cutter movable around the periphery of a heel seat to trim the surplus stock therefrom, adjustable means for controlling the path of said rotary cutter, a dial provided with size designations, and means connecting said dial to said controlling means.

- constructed and arranged to vary the path of the cutter in accordance with the setting of the dial so as to trim the heel seat to fit the particular size of heel indicated by the dial.
8. A heel seat fitting machine provided with shoe-positioning means, a rotary cutter movably supported for movement around the periphery of the heel seat of a shoe positioned by said means to remove the surplus stock therefrom, a horseshoe-shaped templet for determining the path of the rotary cutter, means for limiting the movement of said cutter lengthwise of the shoe, an adjustable dial provided with size designations, and connections from said dial to said length-limiting means whereby adjustment of the dial for a particular size will control the movement of the rotary cutter to trim a heel seat corresponding to said size.
9. A heel seat fitting machine provided with shoe-positioning means, a rotary cutter movably supported for movement around the periphery of the heel seat of a shoe positioned by said means to remove surplus stock therefrom, an adjustable templet formed and arranged to limit the movement of the rotary cutter to a horseshoe-shaped path, a dial provided with size designations, and means connecting said dial to said templet to control the spread of said horseshoe-shaped path in accordance with the particular size of heel indicated by the setting of the dial.
10. A heel seat fitting machine having a rotary cutter mounted for movement around the periphery of a heel seat to remove surplus stock therefrom, an adjustable templet formed and arranged to limit the movement of the rotary cutter to a horseshoe-shaped path, a dial provided with size designations, and mechanism connected with said dial and arranged to control the spread of said horseshoe-shaped path and to control in addition the length of said path so that the operation of the machine will conform to the particular size of heel indicated by the setting of the dial.
11. A heel seat fitting machine provided with a shoe support, a rotary cutter movably supported for movement around the periphery of the heel seat of a shoe carried by said support to remove the surplus stock therefrom, an adjustable templet formed and arranged to limit the movement of the rotary cutter to a horseshoe-shaped path, a dial provided with size designations, and mechanism connected with said dial and arranged simultaneously both to control the spread of said horseshoe-shaped path and to control the length of said path so that the operation of the machine will conform to the particular size of heel indicated by the setting of the dial.
12. A heel seat fitting machine having a knife movable transversely across the heel seat of a shoe to be operated upon, from one edge to the other of the sole of the shoe, to make a breast cut, means for adjustably supporting said knife in the machine, means for adjusting the position of said supporting means to determine the position of the breast cut, a dial provided with size designations, and connections between said dial and said support-adjusting means arranged to control the position of said breast cut in accordance with the size of heel indicated by the dial.
13. A heel seat fitting machine provided with a shoe support, a rotary cutter movably supported in said machine for movement around the periphery of the heel seat of a shoe carried by the support to trim surplus stock therefrom, a carriage movable in a direction parallel to the length of the shoe, a transversely operating knife supported on said carriage for movement across the shoe to make a cut at the heel breast line thereof, a stop upon said carriage adapted to limit the extent of movement of the rotary cutter away from the heel end of the shoe, a dial provided with size designations, and means connecting said dial to said adjustable carriage constructed and arranged to determine the position of the carriage in such a manner that the extent of the cutting action of the rotary cutter and the position of the cut made by the breast cutter will be in accordance with the size of heel indicated by the setting of said dial.
14. A heel seat fitting machine provided with a shoe support, a rotary cutter movable around the heel seat of a shoe carried by said support to trim surplus stock therefrom, a supporting carriage adjustable in a direction parallel to the length of the shoe, a stop upon said carriage arranged to limit the extent of movement of the rotary cutter away from the heel end of the shoe, a dial provided with graduations corresponding to various styles of heels, and means connecting said dial to said adjustable support arranged to position said support upon the machine so that it will control the cutting action of the rotary cutter in accordance with the style of heel indicated by the dial.
15. A heel seat fitting machine provided with shoe-positioning means, a carriage upon said machine movable in a direction parallel to the length of a shoe positioned by said means, a knife movably supported upon said carriage for transverse movement across the heel seat of the shoe from one edge to the other of the sole of the shoe adjacent to the heel breast line thereof, a dial provided with graduations corresponding to the styles of heels to be applied, and means connecting said dial to said carriage constructed and arranged to position said

- transverse cut in accordance with the style of heel indicated by the dial.
16. A heel seat fitting machine provided with shoe-positioning means, a carriage on said machine adjustable in a direction parallel to the length of the shoe, a cutter movably supported on the carriage, a pair of graduated rotary dials, means for adjusting said carriage to determine the operating position of said cutter with respect to a shoe positioned by said positioning means, and means for connecting each dial to said adjusting means.
17. A heel seat fitting machine provided with shoe-positioning means, a cutter supported for movement around the heel seat of a shoe positioned by said means, means for controlling the path of movement of said cutter arranged to be adjusted transversely and longitudinally of the shoe, a pair of graduated rotary dials, means connecting one of said dials to both of said controlling means, and means connecting the other dial to one of said controlling means whereby adjustment of said dials will vary the path of movement of said cutter.
18. A heel seat fitting machine provided with shoe-positioning means, a trimming cutter for removing the peripheral portion of the heel seat of a shoe positioned by said means, a breast cutter for making a heel breast cut at the forward end of the heel seat, adjustable means for controlling the path of movement of each of said cutters, a pair of rotary dials provided with graduations, and mechanism for adjusting each of said controlling means, one of said dials being connected with one adjusting mechanism and the other of said dials being connected with each of said adjusting mechanisms.
19. A heel seat fitting machine provided with shoe-supporting means, an adjustable templet, a cutter movable under the guidance of said templet around the periphery of the heel seat portion of a shoe carried by said supporting means, means for adjusting the templet to control the spread of the path of the cutter, means for limiting the movement of the cutter lengthwise of the templet, a dial provided with size designations, means connecting said dial with said spread controlling means and length-limiting means, a dial provided with style designations, and means connecting said latter dial to the means for limiting the extent of movement of the cutter lengthwise of the templet to determine said extent of movement for any particular setting of the size dial.
20. A heel seat fitting machine provided with shoe-supporting means, a movable cutter arranged for movement around the periphery of the heel seat of a shoe carried by said supporting means, means for guiding said cutter arranged for adjustment transversely of the length of the shoe, adjustable means for limiting the movement of the cutter longitudinally of the shoe, said last-named means being provided with an internally threaded sleeve, a dial provided with style designations and having a tubular extension externally threaded to mesh with the threads in said sleeve, and a dial provided with size designations having a screw member threaded into the bore of said tubular extension and arranged to control said first-named adjusting means, the threads inside and outside of the tubular extension attached to the style dial being arranged in opposite directions.
21. A heel seat fitting machine having a movable cutter adapted to be moved around the periphery of the heel seat of a shoe, a two-part templet controlling the path of movement of said cutter, each of the parts of said templet being pivotally mounted upon the machine, a graduated dial, means for adjusting the parts of said templet to vary the shape of the path of movement of the rotary cutter, and means connecting said dial to said templet-adjusting means whereby adjustment of said dial varies the path of movement of said cutter.
22. A heel seat fitting machine having shoe-positioning means, a rotary cutter movable around the periphery of the heel seat of a shoe positioned by said means to trim the surplus stock therefrom, a templet for controlling the path of movement of the cutter, a lever for adjusting the parts of said templet, a dial provided with size designations, and a cam surface interposed between said dial and said lever and formed and arranged so that equal movements of the dial result in similar movements of the lever to adjust the parts of the templet.
23. A heel seat fitting machine provided with shoe-supporting means, a rotary cutter movable around the periphery of the heel seat portion of the shoe supported by said means, a sliding table supporting said cutter to permit it to be moved into and out of operative position with respect to the shoe, an adjustable templet on said table to control the path of movement of the cutter, a lever for adjusting said templet, a dial mounted on the frame of the machine for adjusting said templet in accordance with the size of the heel to be applied, and a slot and roll connection between said dial and said lever allowing the movement of the dial to be transmitted to the lever in any position of the table.
24. A heel seat fitting machine provided with a sliding table, an adjustable templet mounted on said table, a lever for adjusting said templet, and means mounted on the frame of the machine for controlling the adjustment of the templet comprising a grooved bar mounted for parallel movement with respect to the direction of the path of

movement of the table and a roll on said lever entering said groove whereby the co-action of the adjusting means and the template controlling lever is undisturbed by 5 movements of the table from one position to another.

25. In a machine of the character described, a knife for cutting a tapered flap extending across a piece of stock by slitting 10 the stock transversely substantially from edge to edge with one edge of the cut extending through a surface of the stock and the other edge of the cut lying beneath the surface of the stock, means for moving the 15 knife across the stock in a path approximately at right angles to the edge of the stock, and means for lifting said flap as the cutting action progresses.

26. In a machine of the character described, a knife, means for moving the knife forward and back across the surface of a 20 piece of leather from one edge to the other to cut a flap from said surface, and a plow arranged for movement parallel to the 25 length of the cut to lift said flap out of the way of the knife as the cutting action progresses.

27. In a machine of the character described, a knife, means for moving the knife forward and back across a piece of stock 30 from one edge to another, said knife being provided with a cutting edge transverse of the direction of movement of said knife and adapted at a single stroke to cut a flap extending across said stock from side to side 35 in the direction of the movement of the knife, and a plow constructed and arranged for movement with the knife lengthwise of the flap to lift the flap as the cutting action 40 progresses, said plow being positioned at an angle to said cutting edge and having a point closely adjacent thereto.

28. In a machine of the character described, a sliding bar, a knife carried by 45 said bar, means for moving the bar in a direction substantially at right angles to the edge of a piece of stock to be operated on, said knife being provided with a cutting edge transverse to the length of the bar, 50 another cutting edge substantially parallel to the length of the bar arranged so that said knife by movement across a piece of stock at an angle to the surface of the stock will cut a tapered flap extending trans- 55 versely of the stock, and means attached to said bar constructed and arranged to lift said flap as the cutting action progresses.

29. In a machine of the character described, a sliding bar, a knife carried by said 60 bar and provided with a cutting edge transverse to the length of the bar and another cutting edge substantially parallel to the length of the bar, arranged so that said knife by movement across a piece of stock at an angle to the surface of

the stock will cut a tapered flap extending transversely of the stock, and a plow supported for movement with said knife and arranged to lift said flap as the cutting action progresses, said plow having its point 70 adjacent to the transverse cutting edge disposed substantially parallel to the lengthwise cutting edge.

30. In a machine of the character described, a sliding bar, a cutting knife carried by said bar, a presser foot supported for movement in advance of said knife, and a tapered roll upon said presser foot arranged to press the leather at one end of the roll more than at the other. 75

31. In a machine of the character described, a sliding bar, a knife carried upon said bar provided with a cutting edge transverse to the cutting bar, and a presser foot supported upon said bar for movement in 85 advance of the knife, said presser foot having a roll tapered from one end to the other arranged to bear against the surface of the stock operated upon ahead of said knife to press the portion of the stock engaged by 90 the larger end of the roll harder than the other portions as the cutting action progresses.

32. In a machine of the character described, a sliding bar, a cutting knife carried by said bar provided with angularly arranged edges, means for supporting said knife upon said bar, said means and said bar being provided with coacting arcuate surfaces having their center of curvature in 100 one of said sharpened edges, and a screw arranged to clamp said supporting means to said bar in adjusted position.

33. In a machine of the character described, a sliding bar, a cutting knife carried by said bar and provided with substantially rectilinear angularly arranged edges, and a screw arranged to clamp said knife upon said bar arranged, when released, to allow tilting adjustment of said knife 110 upon the bar about one of said edges.

34. In a machine of the character described, a sliding bar, a cutting knife carried by said bar and provided with angularly arranged edges, and means for clamping said knife to said bar constructed and arranged, when released, to allow universal adjustment of said cutting edges within a 115 limited range.

35. In a machine of the character described, a sliding bar, a member movably associated with said bar, said member and said bar having coacting arcuate surfaces, a knife blade supported upon said member having angularly arranged cutting edges, 120 one of which is substantially parallel to the direction of movement of the bar, said arcuate surfaces being curved about a center located in said last-named cutting edge, and means for clamping said member to said bar 125 130

arranged, when released, to permit adjustment of the position of the member and its attached knife blade with respect to the bar.

36. In a machine of the character described, shoe-positioning members, a shoe support adapted to be elevated to press a shoe against the positioning members, a plurality of tools movably supported for movement toward and away from the work, individual means for actuating the supports for said tools, and means constructed and arranged to be actuated by either of said tool-support actuating means for raising the shoe support during the time when the corresponding tool is acting upon the work.

37. In a machine of the character described, shoe-positioning members, a shoe support arranged to be elevated to push a shoe into engagement with the positioning members, a plurality of cutter-supporting members adapted to be moved alternately into position for the operation of a cutter on the work, separate actuating members for moving said supports into operative position, means for elevating said work support, and resilient connections of different strength between said individual actuating members and said work support elevating means.

38. In a machine of the character described, shoe-positioning members, a shoe support adapted to be elevated to press a shoe against the positioning members, a pair of control levers, and means constructed and arranged to be actuated alternatively by either of said control levers for raising the shoe support and thereby pressing the shoe against the positioning members.

39. In a heel seat fitting machine, work-positioning and supporting members movably supported for engagement in the rand crease of a shoe, actuating links for said members and a sliding cam constructed and arranged to actuate said links to bring the work-supporting members into engagement with the shoe.

40. A heel seat fitting machine provided with shoe-positioning means, a rotary cutter arranged for movement about the heel seat of a shoe positioned by said means to trim surplus stock from the periphery of the heel seat of the shoe, adjustable means for controlling the path of movement of the cutter, and a motor carrying said cutter on its rotor shaft and arranged for movement with the cutter as the latter is moved about the heel seat of the shoe.

41. A heel seat fitting machine having a shoe support, a rotary cutter for trimming the periphery of the heel seat of a shoe carried by said support, control levers for guiding said cutter about the heel seat of the shoe, and an electric motor carrying said cutter on its rotor shaft and supported upon one of said control levers.

42. A machine for operating upon shoes

having a tool movable into and out of operative relation to a shoe to be operated upon, a motor for actuating said tool, means for positively controlling the relative movement of the tool and a shoe as the tool operates on the shoe, and controlling means for said motor arranged to connect the motor with its source of power when the tool is moved towards operating position and to disconnect the motor from its source of power when the tool is moved away from operating position.

43. A heel seat fitting machine having shoe-positioning means, a cutter arranged for movement into and out of operative relation to the heel seat portion of the sole of a shoe positioned by said means and operable to trim surplus material from the periphery of the heel seat of said shoe, a motor arranged to actuate the cutter, and means arranged to connect the motor with its source of power when the cutter is moved into operative relation to the shoe and to disconnect the motor from its source of power when the cutter is moved out of operative relation to the shoe.

44. A heel seat fitting machine having shoe-positioning means, a rotary cutter arranged for movement into and out of operative relation to the heel seat portion of the sole of a shoe positioned by said means and operable to trim surplus material from the periphery of the heel seat of said shoe, a motor carrying the cutter upon its rotor shaft and arranged for movement with the cutter, and means arranged to connect the motor with its source of power when the cutter is moved into operative relation to the shoe and to disconnect the motor from its source of power when the cutter is moved out of operative relation to the shoe.

45. In a machine of the character described, a movable cutter, a carriage for said cutter movable into and out of operative position, a substantially horseshoe-shaped guide arranged to limit movement of the cutter relatively to the carriage to a substantially horseshoe-shaped path, an electric motor for actuating said cutter, and an electric switch actuated by the movements of said carriage to disconnect said motor from its source of power when the carriage is moved to inoperative position.

46. A heel-seat fitting machine having a motor, a trimming cutter mounted on the rotor shaft of the motor, means for moving the motor and the cutter bodily about the periphery of the heel-seat portion of the sole of a shoe to trim surplus material therefrom, and a substantially horseshoe-shaped guide arranged to control the path of movement of the motor and the cutter during the trimming operation.

47. A heel-seat fitting machine having a cutter movable in an approximately horse-

- shoe shaped path about the periphery of the heel-seat of a shoe to trim surplus stock therefrom, adjustable means for controlling the path of said cutter, a graduated dial, 5 and means for controlling the extent of the forward movement of the cutter in its approximately horseshoe-shaped path about the periphery of the heel-seat in accordance with the setting of the dial.
- 10 48. A heel-seat fitting machine having a movable cutter adapted to be moved around the periphery of the heel-seat of a shoe to trim surplus material from the sole thereof, a templet having a guideway corresponding 15 in shape to the contour of the heel-seat of a shoe, a graduated dial, and means for controlling the extent of the forward movement of the cutter about the periphery of the heel-seat in accordance with the setting 20 of said dial.
49. A heel-seat fitting machine having a movable cutter adapted to be moved around the periphery of the heel-seat of a shoe to trim surplus material from the sole thereof, 25 a templet comprising a plurality of relatively movable parts provided with a guideway formed and arranged to guide the movement of the cutter in an approximately horseshoe-shaped path about the 30 heel-seat of the shoe, a graduated dial, and means to limit the extent of the forward movement of the cutter about the periphery

of the heel-seat in accordance with the setting of the dial.

50. A heel-seat fitting machine having a 35 cutter arranged to be moved about the periphery of the heel-seat of a shoe, a templet comprising two parts pivotally mounted to permit adjustment of the templet in accordance with the width of the heel-seat of the 40 shoe to be operated upon, said templet being provided with a substantially horseshoe-shaped guideway arranged to control the path of movement of the cutter, a graduated dial, and means for controlling the extent of 45 the forward movement of the cutter about the heel-seat in accordance with the setting of said dial.

51. A heel-seat fitting machine provided 50 with shoe-positioning means, a cutter supported for movement about the periphery of the heel-seat of a shoe positioned by said means to remove surplus stock therefrom, an adjustable templet formed and arranged to limit the movement of the cutter in a horse- 55 shoe-shaped path, a graduated dial, and means for controlling the extent of the forward movement of the cutter about the heel-seat in accordance with the setting of the 60 dial.

In testimony whereof I have signed my name to this specification.

WILLIAM C. STEWART.

CERTIFICATE OF CORRECTION.

Patent No. 1,661,391.

Granted March 6, 1928, to

WILLIAM C. STEWART.

It is hereby certified that error appears in the printed specification of the above numbered patent requiring correction as follows: Page 1, line 30, for the word "successively" read "successfully"; page 3, line 21, before the word "means" insert the word "by", and line 107, for the word "applied" read "supplied"; and that the said Letters Patent should be read with these corrections therein that the same may conform to the record of the case in the Patent Office.

Signed and sealed this 30th day of April, A. D. 1929.

M. J. Moore,
(Seal) Acting Commissioner of Patents.
